UNITED STATES PATENT OFFICE.

LE ROY WILLOUR, OF ASHLAND, OHIO.

JACK.

1,161,099.

Specification of Letters Patent. Patented Nov. 23, 1915.

Application filed January 16, 1915. Serial No. 2,705.

To all whom it may concern:

Be it known that I, LE ROY WILLOUR, a citizen of the United States, residing at Ashland, in the county of Ashland and State of 5 Ohio, have invented certain new and useful Improvements in Jacks, of which the following is a specification.

My invention relates to improvements in lifting jacks, which have become known to 10 the trade as "tire savers."

An important object of the invention is to provide a lifting jack of the above mentioned character, which is strong, and has the operating parts thereof assembled in a 15 compact manner.

A further object of the invention is to provide a lifting jack of the above mentioned character, having means whereby the lift-bar may be manually adjusted into engagement 20 with the load, prior to the same being mechanically raised.

A further object of the invention is to provide novel and simple means to effect the longitudinal movement of the lift-bar or 25 lift-member.

A further object of the invention is to provide novel and simple means for permanently retaining the parts of the jack assembled.

30 Other objects and advantages of the invention will be apparent during the course of the following description.

In the accompanying drawings forming a part of this specification and in which like 35 numerals are employed to designate like parts throughout the same, Figure 1 is a side elevation of a lifting jack embodying my invention, Fig. 2 is a longitudinal sectional view taken on line 2—2 of Fig. 1, Fig. 3 is an edge elevation of the jack, Fig. 4 is a horizontal sectional view taken on line 4—4 of Fig. 1, Fig. 5 is a similar view taken on line 5—5 of Fig. 1, Fig. 6 is an enlarged detail section taken on line 6—6 of Fig. 3, 45 Fig. 7 is a perspective view of a vertically movable lift casing or member, and, Fig. 8 is a central longitudinal sectional view through a jack embodying a slightly different 50 ent form of the invention.

In the drawings, wherein for the purpose of illustration is shown a preferred embodiment of my invention, the numeral 10 designates a preferably hollow standard, secured upon a base or foot 11.

55 Formed upon one edge of the standard 10, preferably adjacent the upper end thereof, is

a lateral upstanding bracket or arm 12, provided at its upper end with an apertured head 13, more clearly shown in Figs. 3, 6. and 8.

60

The numeral 14 designates an operating lever having its upper end forked, as more clearly shown in Fig. 3, providing spaced arms 15, which straddle the head 13, and are pivoted thereto by means of a transverse pin 65 16 or the like. The arms 15 extend upwardly beyond the pivot 16 for a substantial distance and are provided with laterally extending shifting members 17, shown more clearly in Fig. 4. The shifting members 70 preferably embody trunnions or studs 18, rigidly secured to the arms 15, with rollers or wheels 19 thereon. While I prefer to mount these rollers upon the studs 18, it is to be understood that the invention is not restricted to the same, as some degree of success may be obtained without them.

Having slidable engagement with the upper portion of the standard 10 is a lift-member or casing 20, which is preferably hollow 80 to receive the standard. This lift-member is provided preferably near its upper end with outwardly bulging transverse pockets 21, which are preferably vertically inclined and afford preferably vertically inclined 85 transverse tracks or flanges 22, preferably arranged upon the interior of the lift-member or casing. The rollers 19 included in the shifting members operate within the pockets 21 and engage the tracks or flanges 90 22, and when the lift-member is in the upper position and the operating handle 14 in the lower position, the rollers 19 enter preferably curved recesses 23, at the rear ends of the tracks 22, whereby these parts are locked 95 in the active position so that they cannot be disturbed by pressure tending to move the lift-member or casing 20 downwardly. The lift-member has its rear side formed open, as more clearly shown in Fig. 7, and is provided with inwardly extending guide lugs 100 24, slidably engaging with the standard 10, but clearing the arm or bracket 12. The rear edges of the lift-member or casing 20, at the top thereof, are connected by a transverse strip or member 25, forming a preferably rectangular opening 26. The lift-member or casing 20 is provided at its top and upon the forward portion thereof with a tooth or teeth 27, shown more clearly in 105 Figs. 6 and 7, and rearwardly of the tooth or teeth 27 with transversely spaced teeth 28,

105

110

arranged preferably near the central portion of the opening 26, these teeth being of course preferably cast integral with the lift-member or casing.

5 The numeral 29 designates a lift-bar provided at its upper end with a suitable head 30. This lift-bar is preferably provided upon its opposite sides with longitudinal grooves or channels 31, receiving the teeth 28 therein. At its forward edge, the lift-bar 29 is provided with a set of teeth 32, to engage with the tooth or teeth 27 and near its opposite longitudinal edge and within the channels 31 with sets of teeth 33, to engage 10 with the teeth 28. It is thus seen that three sets of teeth carried by the lift-bar simultaneously engage with the teeth 27 and 28, for securing the lift-bar 29, to the lift-member or casing 20, and that the lift-bar may be 15 readily manually longitudinally adjusted up or down, with respect to the lift-member or casing, and locked thereto in adjustment at a desired vertical position. The longitudinal adjustment of the lift-bar 29 with respect to the lift-member or casing is independent of the longitudinal movement of the lift-member or casing by the operating lever 14. Some degree of success may be 20 obtained by dispensing with the lift-bar, in which case the lift-member or casing 20, or an extension thereof will engage the load.

The form of jack shown in Fig. 8, differs from the first form of the invention only in the construction and arrangement of the 25 teeth carried by the lift-member or casing and the lift-bar. In Fig. 8, the lift-bar 29 is provided with only one set of teeth 34, upon the forward longitudinal edge thereof, adapted to engage with a tooth 35, formed upon the upper end of the lift-member or casing 20, adjacent the forward edge thereof. The teeth 34 have preferably curved lower recesses 36, and the tooth 35 is 30 preferably correspondingly rounded. This 45 type of jack is of a slighter construction and while lighter is not as strong as the jack embodying the first form of the invention.

As more clearly shown in Fig. 2, the lift-bar 29 is provided preferably at its lower end with a depending finger 37 adapted when bent laterally a sufficient distance to engage with an inwardly extending stop-lug 38, formed upon the inner surface of the side 55 of the standard 10, but does not engage with the inner surface of the standard 10, to impede the movement of the lift-bar within its operative limits. The function of this tongue and stop-lug is to retain the lift-bar 60 and standard permanently assembled. The standard 10 is provided preferably adjacent its top with a depending stop-finger 39,

adapted to be bent laterally and outwardly to engage with the lower end of the lift-member or casing 20, thus permanently 65 maintaining the same upon the standard and not interfering with the proper longitudinal movement of the lift-bar. It is to be understood that the form of jack shown in Fig. 8 is also provided with identical means 70 for preventing the separation of the standard, lift-bar, and lift-member.

In operation, the jack is placed beneath the load to be raised, and the operating lever 14 is swung to the upper position to lower 75 the lift-member or casing 20. The lift-bar is now manually elevated or adjusted until the same engages with the load and of course is locked to the lift-member or casing. The operating lever 14 is then swung down- 80 wardly to assume the lowermost position and the lift-bar will raise the load.

Attention is called to the fact that in operation, the arms 15 enter the lift-member or casing 20, upon opposite sides of the lift-bar 29. This mode of operation enables the parts of the jack to be arranged in a compact manner, dispensing with the laterally projecting members, ordinarily present in jacks of this general type. 90

It is to be understood that the forms of my invention herewith shown and described are to be taken as preferred examples of the same, and that various changes in the shape, size, and arrangement of parts may be resorted to without departing from the spirit of the invention or the scope of the subjoined claims. 95

Having thus described my invention, I 100 claim:—

A jack of the character described, comprising a standard; a tubular lift casing slidably mounted upon the standard and provided with transverse outwardly bulging pockets upon its opposite sides, the pockets having their upper walls vertically inclined and provided near their lower ends with recesses; an operating lever pivotally connected with the standard and having its upper end forked to provide arms which 105 project into the lift casing inwardly of and near the pockets; and rollers pivotally connected with the ends of the arms and arranged upon the outer side thereof to enter the outwardly bulging pockets and engage 110 with the inclined walls thereof having the recesses. 115

In testimony whereof I affix my signature in presence of two witnesses.

LE ROY WILLOUR.
